UNITED STATES PATENT OFFICE

143,204

DESIGN FOR A BATH TUB

Ethel L. Fleischhauer, La Fayette, Ind.

Application May 25, 1945, Serial No. 119,730

Term of patent 7 years

(Cl. D4—4)

To all whom it may concern:

Be it known that I, Ethel L. Fleischhauer, a citizen of the United States, residing at La Fayette, in the county of Tippecanoe and State of Indiana, have invented a new, original, and ornamental Design for a Bath Tub, of which the following is a specification, reference being had to the accompanying drawing, forming a part thereof.

I claim:

The ornamental design for a bath tub, as shown.

ETHEL L. FLEISCHHAUER.
